UNITED STATES PATENT OFFICE

JOHN W. UPP AND WILLIAM K. RANKIN, OF SCHENECTADY, NEW YORK, ASSIGNEES TO
GENERAL ELECTRIC COMPANY, A CORPORATION OF NEW YORK

ELECTRIC SWITCH

Application filed August 4, 1927. Serial No. 210,653.

Our invention relates to electric switches of the fluid break type and particularly to those switches which are adapted for the control of large capacity power transmission circuits. One object of our invention is the provision of a switch having various improved features of construction resulting in greater efficiency, accessibility, and reliability at a minimum cost of manufacture.

A further object of our invention is to provide a fabricated switch, in which the switch enclosing and mechanism supporting structure and bushing mountings are made up of sheet metal parts pressed or bent to shape and particularly adapted for being secured together by electric arc welding, preferably by the metallic arc process.

Our invention will be better understood from the following description taken in connection with the accompanying drawings, and its scope will be pointed out in the appended claims.

Referring to the drawings, Fig. 1 is a side elevation partly in cross section of a switch embodying our invention; Fig. 2 is a cross sectional view through the upper portion of the switch showing the operating mechanism; Fig. 3 is a cross section on the line 3—3 of Fig. 2; Fig. 4 is an elevation partly in section of a modified form; and Fig. 5 is a section on line 5—5 of Fig. 4 drawn to a larger scale.

The vessel or casing enclosing the switch contacts and the insulating liquid, in which they are immersed, comprises essentially the sheet metal cylinder 1, the bottom end head 2 and the removable cover 3, the casing being constructed to withstand relatively high pressures. The bottom end head and the cover comprise dome-shaped members pressed up from sheet metal stock and preferably both have the same form and dimensions whereby the same dies serve for the making of both. The bottom end head has its flanged edge fitting within and welded to the cylinder 1, thereby forming the tank. Welded respectively to the upper edge of the cylinder and to the flanged edge of the cover are the clamping rings or flanges 4 and 5, each being provided at intervals with lugs 6 engaged by

clamping bolts 7. By the use of a suitable gasket between the rings 4 and 5, the cover and tank may be clamped together by the bolts 7 to make a gas-tight connection. Inasmuch as the cover and the bottom end head have the same diameter corresponding with the inside diameter of the cylinder, the two rings 4 and 5 differ slightly in form and diameter in order to properly fit the members to which they are secured. Within the tank 55 is the insulation lining 8 supported from the bottom of the tank by the rods 9 and connected with the bottom is the drain pipe 10. Extending through the cover are the two insulator bushings 12 and 13 each having a 60 terminal connector 14 at its upper end and a fixed switch contact 15 at its lower end. The fixed contacts are adapted to be bridged by the movable contact member 16 which is actuated by the operating rod 17 extending 65 up to the operating mechanism above. For supporting the insulator bushings the cover is provided with suitable openings into which fit and are welded the rings 20 each shown having the integral outward flange 21 and 70 the welded inward flange 22. The lower flange 22 has an integral outward extension or lip 23 which for greater strength is braced from the upper flange 21 by the plate 24 also attached by welding. The lip 23 is provided for the purpose of supporting the switch from a suitable supporting structure, 75 not shown, or fastening the tanks together if they are floor mounted, the long line of the welded connection between the ring 20 and 80 the cover head serving to stiffen the cover and to distribute the force incident to the weight of the switch over a large area of the cover. Within the ring 20 is the current transformer 85 26 having terminals brought out through 90 openings in ring 20 and secured to the top of the ring by bolts, not shown, is the cover ring 27 to which the flange 28 of the bushing is secured by the bolts 29, suitable gaskets being used to make the joints tight.

The guide for the operating rod 17 comprises the V-shaped member 32 of insulating material, the two upper ends of which are shown secured by angle brackets and bolts 95 to the lower flange 22 of the ring 20 while 100

the intermediate portion engages the operating rod at the point of the V adjacent the fixed contacts 15. The guide having a sharp incline as shown and being devoid of any flat surface between the contacts upon which carbon might collect and partially bridge the gap between the contacts, the possibility of a short circuit between the contacts from this cause is greatly reduced if not entirely eliminated.

The switch operating mechanism by which vertical movement is imparted to the operating rod is housed for the most part in an upward extension of the cover, a rectangular opening being cut away in the central portion of the head comprising the cover. This extension is formed in part of an open rectangular box-like member 35 to the top of which is detachably connected by bolts 36 the covering member 37. Both members 35 and 37 are constructed of sheet metal, the former being welded to the cover head thereby stiffening and strengthening the same around the opening therein and the latter being built up of sheet metal plates welded together and secured to member 35 in a gas-tight manner. Secured to and depending from the member 37 are the spaced plates 38 and 39 which support the pin 40 on which is pivoted the double lever 41. At one end, this lever is pivoted to the toggle links 42 and 43, the latter being secured to shaft 44 journalled in the walls of member 37. Near its other end this lever is pivoted to lever 45 comprising the straight line motion mechanism, the ends of which lever are pivoted respectively to the operating rod 17 and to the link 46. It will be noted that the intermediate pivot of lever 45 is slightly displaced from the straight line joining the two end pivots thereof. As a result of this construction the rod 17 moves in a more nearly straight line without the use of an excessively long link 46. This straight line motion mechanism is described and claimed in a patent of William K. Rankin, No. 1,754,179, granted April 8, 1930, and assigned to the same assignee as the present application. The downward or switch opening movement of the mechanism is checked by the dash pots 48 which are supported by the plates 38 in position to be engaged by the double lever 41. The upward or closing movement of the mechanism is checked by the spring buffer 49 positioned to be engaged by the double lever 41. The buffer is mounted in the top wall of the covering member 37 and has an outwardly extending adjusting member 50 by means of which the tension of the buffer may be adjusted from the exterior of the enclosing casing. On one end of the shaft 44 and outside the cover member 37 is the crank 52 which through link 53 and rod 54 connects with the closing spring 55 also located outside of the cover member 37. Rod 54 is guided by the lug

56 and on its free end has a nut 57 by which the tension of the spring 55 may be adjusted. For adjusting the limiting position of the toggle links 42, 43, link 43 is provided with an extension 59 and an adjusting screw 60 is threaded into the cover member 37 to engage the extension, the screw being thus accessible from the exterior of the casing. On the opposite end of the shaft 44 is the operating crank 62 to which is pivoted the main actuating rod 63. This rod at one end connects through the bell crank 64 with the rod 65 to which connects the switch actuating motor mechanism, not shown. The other end of rod 63 has an adjustable connection 66 with rod 67 leading to another switch unit which is to be operated simultaneously with the unit shown.

Weather protection for the parts located out-side of the pressure casing comprises the sheet metal frame 70 having ends 71 approximately semi-circular in form secured by the bolts 36 to the cover structure. Cooperating with this frame is the light sheet metal cover 72, bolts 73 being provided by which it is held down to the frame 70. The weather enclosure thus provided is extended by means of the nipple 75, the elbow casing 76 and pipe 77 to enclose the rod 63, bell crank 64 and rod 65. The rod 67 connecting with the next unit is enclosed by the pipe 78 having a slip connection with the nipple 79. At 80 is shown a semaphore for indicating whether the switch is in closed or open position.

In the modified form illustrated by Figures 4 and 5 the cylinder 1 has welded to it both the bottom head, not shown, and the top or cover head 85, the operating mechanism being arranged entirely below the contour of the cover head. Since the top of the head accordingly is further above the fixed contacts the insulator bushings 86 are longer than in the form illustrated by Fig. 1. The spaced plates 87 by which the mechanism is supported are bolted to the cover head 85 and preferably are made in sections small enough to pass through the manhole in the top of the cover. Secured to the cover head adjacent one plate 87 is the box 88 enclosing the rod 89 and lever 90. The ends of the box connect with nipples 91 also secured to the cover head. Access to the interior of the switch casing for the assembly and care of the apparatus therein is obtained through a manhole shown closed by the cover 92 and for a similar purpose the box 88 is provided with a suitable opening shown closed by the plate 93. The construction otherwise is substantially the same as that shown in Fig. 1.

We have chosen the particular embodiments described above as illustrative of our invention and it will be apparent that various modifications may be made without departing from the spirit and scope of our in-

vention which modifications we aim to cover by the appended claims.

What we claim as new and desire to secure by Letters Patent of the United States, is:

- 5 1. An electric switch comprising a sheet metal vessel having openings in the top thereof, insulator bushings extending through a pair of said openings, a bushing supporting ring disposed in each of said bushing openings and having a welded connection with the top, and a sheet metal box-like structure surrounding another of said openings and having a welded connection with the top adjacent said opening, a switch operating mechanism depending within said opening and carried by said box-like structure, said bushing supporting rings and box-like structure serving to strengthen and increase the rigidity of said top, and means associated with said top for supporting said circuit breaker.
- 10 2. An electric switch comprising a vessel having a sheet metal cover provided with openings therein, an insulator bushing extending through each of said openings, a bushing supporting ring arranged in each opening and having a welded connection with the cover, each of said rings having an outwardly extending flange portion adapted to said top, said bushing supports each having an outwardly extending flange by which the switch is adapted to be supported.
- 15 3. An oil circuit breaker comprising a casing containing oil and fixed and movable contacts immersed therein, said casing including a cover having an aperture therein, a removable portion covering said aperture, external means for removably securing said portion to the cover, insulator bushings extending through said cover and supporting the fixed contacts, switch operating mechanism secured to and removable with said removable portion, said mechanism partly depending into the switch casing through said aperture, and an operating rod having a connection with said mechanism, said connection extending through and journaled in a wall of said removable portion.
- 20 4. An electric switch comprising a pressure casing having switch contacts and contact operating mechanism therein, a removable portion mounted at the top of said casing, a buffer spring mounted on a wall of and within said portion for said mechanism and means operable from the exterior of said portion for adjusting said spring.
- 25 5. An oil circuit breaker comprising a contact enclosing tank, a sheet metal cover therefor having a generally rectangular opening therein, a switch operating mechanism located above said cover and projecting through said opening, a generally rectangular sheet metal box-like structure surrounding said opening and welded to said sheet metal cover adjacent the opening therein, a removable cover for said box-like portion, and means for securing said box cover to said box portion, said switch operating mechanism being mounted within and supported by said removable cover, a shaft supported by said mechanism journaled in and extending through said removable cover, and a closing spring operatively connected to said shaft externally of said cover tending to move said mechanism to closed circuit position.
- 30 6. A circuit breaker comprising a sheet metal vessel having openings in the top thereof, insulator bushings extending through a pair of said openings, a bushing supporting ring disposed in each of said bushing openings and having a welded connection with the top, and a sheet metal box-like structure surrounding another of said openings and having a welded connection with the top adjacent said opening, a switch operating mechanism depending within said opening and carried by said box-like structure, said bushing supporting rings and box-like structure serving to strengthen and increase the rigidity of said top, and means associated with said top for supporting said circuit breaker.
- 35 7. A circuit breaker comprising a tank within which fixed and movable contacts are disposed, a dome-shaped cover for said tank, means for supporting switch operating mechanism for said contacts from said cover comprising a pair of supporting plates mounted in depending relation with respect to said cover, and a dash pot for said operating mechanism secured to and carried by said supporting plates.
- 40 8. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 45 9. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 50 10. An electric switch comprising a pressure casing containing insulating liquid and fixed and movable contacts immersed therein, said casing including a cover having a removable portion, external means for removably securing said portion to the cover, insulator bushings extending through said cover and supporting the fixed contacts, and switch operating mechanism secured to and removable with said removable portion, an operating rod having a connection with said mechanism which connection extends through and is journaled in a wall of said removable portion, and a separately removable cover for said rod and connection.
- 55 11. An oil switch comprising a contact enclosing tank, a dome shaped sheet metal cover therefor having a generally rectangular opening therein, a switch operating mechanism located above said cover and projecting through said opening, a generally rectangular sheet metal box-like structure surrounding said opening and welded to said sheet metal cover adjacent the opening therein, a removable cover for said box-like portion, and means for securing said box cover to said box portion, said switch operating mechanism being mounted within and supported by said removable cover, a shaft supported by said mechanism journaled in and extending through said removable cover, and a closing spring operatively connected to said shaft externally of said cover tending to move said mechanism to closed circuit position.
- 60 12. A circuit breaker comprising a sheet metal vessel having openings in the top thereof, insulator bushings extending through a pair of said openings, a bushing supporting ring disposed in each of said bushing openings and having a welded connection with the top, and a sheet metal box-like structure surrounding another of said openings and having a welded connection with the top adjacent said opening, a switch operating mechanism depending within said opening and carried by said box-like structure, said bushing supporting rings and box-like structure serving to strengthen and increase the rigidity of said top, and means associated with said top for supporting said circuit breaker.
- 65 13. A circuit breaker comprising a tank within which fixed and movable contacts are disposed, a dome-shaped cover for said tank, means for supporting switch operating mechanism for said contacts from said cover comprising a pair of supporting plates mounted in depending relation with respect to said cover, and a dash pot for said operating mechanism secured to and carried by said supporting plates.
- 70 14. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 75 15. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 80 16. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 85 17. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 90 18. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 95 19. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 100 20. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 105 21. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 110 22. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 115 23. An electric switch comprising a pressure casing containing insulating liquid and fixed and movable contacts immersed therein, said casing including a cover having an extending portion removable therefrom, supporting plates depending from said portion, insulator bushings extending through said cover and supporting the fixed contacts, and switch operating toggle mechanism mounted on said plates and removable with said removable portion independently of said bushings.
- 120 24. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 125 25. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.
- 130 26. An electric switch comprising a pressure casing having switch contacts and contact operating mechanism therein, said mechanism including a toggle, a removable portion mounted at the top of said casing within which said toggle is mounted, and means extending through and operable from the exterior of said portion for adjusting said toggle.

- lar opening therein, a switch operating mechanism located above said dome shaped cover and projecting through said opening, a generally rectangular sheet metal box-like structure surrounding said opening and welded to said dome shaped member adjacent the opening therein, a removable cover for said box-like portion and means for securing said removable cover in a gas tight manner to said box portion, said switch operating mechanism being mounted within and supported by said box cover, whereby said mechanism is removable as a unit with the box cover.
- 10 12. An oil switch comprising a dome shaped sheet metal cover having an opening therein, a box-like member surrounding said opening and welded to the cover adjacent the opening therein, a removable cover for said box-like portion, and means for removably securing said box cover to the box-like portion in a gas tight manner, said box cover having a hollow raised portion, switch contact operating mechanism mounted within and supported by said box cover, actuating mechanism for said switch operating mechanism located outside of the raised portion of the box cover, and a removable cover for said actuating mechanism.
- 20 20. In witness whereof, we have hereunto set our hands.

JOHN W. UPP.
WILLIAM K. RANKIN.
